UNITED STATES PATENT OFFICE

2,447,988

AMPOULE NECK CUTTER

Louis A. Pierson, Meriden, Conn.

Application January 3, 1946, Serial No. 638,828

5 Claims. (Cl. 49—52)

1

This invention relates to devices for opening liquid filled glass ampoules, and particularly those with elongated necks and hermetically sealed.

In the packing and distribution of pharmaceutical liquids for medicinal and hypodermic uses it is customary for the pharmaceutical packers to fill the ampoules with the desired liquids and seal the same to prevent contamination and to facilitate the distribution thereof. These ampoules are carried by physicians for use when needed. These containers are relatively small, sufficient for one charge for a hypodermic syringe. It is most important that in the opening of said containers no contamination of the contents shall occur. It is necessary in opening the ampoules to break off the neck thereof. This is ordinarily accomplished by the operator using his two hands therefor, and in such process the thin glass frequently splinters and sometimes cuts the hands from which blood may mingle with the contents of the ampoule; and some of the contents may become contaminated from substances on the hand and flow back into the body of the liquid.

In some cases files and abrading elements have been used to weaken the line around the necks of the ampoules to facilitate the breaking along an even line around the neck but difficulty is found in forming such line evenly around the necks, and contamination is sometimes carried by the files and elements upon the surface of the ampoules which may enter the contents when opened. It is an object of this invention to provide a tool that will positively form an even abraded line around the neck of the ampoule thus insuring that the ampoule tip will break off evenly about this abraded line.

A further object of the invention is to provide an ampoule neck cutter tool that may be easily sterilized in the same manner and at the same time as the hypodermic or any other medical or surgical tool, thus insuring against the cutter tool carrying any contamination to the ampoule or its contents.

A further object of this invention is to provide an ampoule neck cutter tool which may be held and operated by one hand while the ampoule is manipulated thereon by the other hand to provide a complete even abraded circle about the neck of the ampoule enabling the neck to be easily and safely broken off.

With these and other objects to be hereinafter stated, I have illustratively exemplified my invention by the accompanying drawing, of which:

Fig. 1 is a perspective view of the ampoule neck cutter tool of this invention;

Fig. 2 is an elevational view, on a larger scale, of cutter carrying lever of the tool;

2

Fig. 3 is a side plan exploded view, partly in section, of the entire tool;

Fig. 4 is an elevational view of the anvil lever of the tool;

5 Fig. 5 is a sectional view on line 5—5 of Fig. 3, showing the cutter details, and

Fig. 6 is a sectional view on line 6—6 of Fig. 3, showing the anvil details.

There is shown at 10 the ampoule neck cutter

10 tool of this invention. This invention includes a cutter carrying lever 11 having an extending boss 12 near one end adapted to be located in a correspondingly shaped aperture 13 in an anvil lever 14. A shaft 15 anchored through transverse apertures 16 in the anvil lever 14 and extending through an aligned transverse structure 17 in the boss 12 serves to journal the two levers together. The anvil lever 14 is curved away at 18 between the journal shaft 15 and its adjacent end 20, thus permitting a limited separation of the anvil and cutter jaw ends of the levers, a spring 21 located in countersunk recesses 22 in the levers serving to normally hold the cutter and anvil jaw ends in such separated position.

25 The anvil and cutter levers have their separated jaw ends shaped, as shown, with a pair of flats 23 and 24 separated by an angular recess 25 in the anvil lever and a similar recess 26 in the cutter lever. When the anvil and cutter jaw ends of

30 levers 11 and 14 are brought together by pivoting them about the shaft 15, the sides of the angular recesses 25 and 26 together outline a square whose sides are very slightly greater than the outside diameter of the neck 27 between the ampoule body 28 and its tip 30.

35 Reciprocably extending through the apex of the angular recess 26 of the cutter jaw end of lever 11 is a cutter plunger 31 about which is located coil spring 32 mounted between the back of the lever 11 and a thumb button 33 secured on the outer end of the plunger 31. The plunger 31 extends through a shaftway in the jaw end lever 11 and terminates in the apex of angular recess 26, where it is reciprocably held by a pin 34 ex-

40 tends across a flat 35 formed in the side of the plunger 31, thereby limiting the reciprocation of the plunger 31. The inner end of the plunger 31 terminates in a point 36 of substantially diamond hardness, either a commercial diamond or a material of suitable hardness such as tungsten carbide or other similar material, thus, in effect, providing a diamond point 36 suitable for cutting or abrading glass.

45 In operation, the cutter tool 10 should be held 50 in the left hand, the thumb resting on the thumb button 33 of plunger 31 directly above the plunger spring 32, with the anvil jaw end of

lever 14 resting on the index finger. The ampoule 28 is placed with its neck 27 between the jaw ends of the tool with the right hand. The left thumb is pressed to close the jaw ends securely about the ampoule neck 27, then the thumb is pressed a little harder, which will bring the diamond hard point 36 into abrading contact with the ampoule neck 27. The ampoule is rotated back and forth while the left thumb is pressed until it is felt that the diamond hard point 36 is cutting the glass of the ampoule neck 27, then the ampoule 28 is rotated completely around. This will cut a complete circle around the ampoule neck 27 and enable the ampoule tip 30 to be easily and safely broken off, without danger of cutting the fingers or contaminating the contents of the ampoule. The tool 10 is of hard metal, preferably completely chromium-plated about the levers and button wherever it may be handled, and may be sterilized along with other surgical tools, thus preventing the tool from contaminating the ampoule neck.

While I have shown and described one embodiment of my invention, together with certain modifications thereof, I wish it to be understood that I do not desire to be limited to the details thereof as various modifications may occur to a person skilled in the art.

Having described my invention I claim as new:

1. An ampoule neck cutter tool comprising a pair of levers pivoted together adjacent one end, yieldable means normally urging their other ends apart, recessed jaws formed on said other ends, the recesses in said jaws being of such size as to receive and loosely hold an ampoule neck therebetween when said jaws are squeezed together, a plunger reciprocably extending through one of said jaws into the recess therein, yieldable means normally urging said plunger away from the recess, thumb receiving means on said plunger for pressing said plunger against said yieldable means and into said recess, and a diamond hard glass cutting point provided on the plunger end within said recess, said first and second mentioned yieldable means being so constructed and arranged that by pressing on said thumb receiving means, the jaws are first squeezed together and thereafter upon continued pressing, the cutter point is moved further into the recess, whereby when an ampoule neck is held in the recesses between the pressed together jaws, the pressed-in plunger will cause its point to cut the ampoule neck as the ampoule neck is rotated.

2. An ampoule neck cutter tool comprising a pair of pivoted recessed jaws, yieldable means normally urging said jaws apart, the pressed together recesses of said jaws being adapted to receive and loosely hold an ampoule neck therein, a cutter plunger reciprocably extending through one of said jaws into said recess and means yieldably resisting the movement of said plunger into said recess, said first and second mentioned yieldable means being so constructed and arranged that by pressing on said plunger, said jaws are first squeezed together and thereafter upon continued pressing the cutter point is moved to contact the ampoule neck within the recess, to cut the ampoule neck as it is rotated within said recesses of said jaws.

3. An ampoule neck cutter tool comprising a pair of jaw members movably secured together, yieldable means normally urging said jaw members apart, at least one of said jaw members having an ampoule neck receiving recess therein, the pressed together jaw members being adapted

to receive and loosely hold an ampoule neck in the recess, a cutter plunger reciprocably extending through one of said jaw members in alignment with the recess and means yieldably resisting the movement of said plunger into said recess, said first and second mentioned yieldable means being so constructed and arranged that by pressing on said plunger said jaw members are first squeezed together and thereafter upon continued pressing the cutter plunger is moved to contact and to cut the ampoule neck as it is rotated within the recess between said jaw members.

4. An ampoule neck cutter tool comprising a pair of jaw members movably secured together, yieldable means normally urging said jaw members apart, at least one of said jaw members having an ampoule neck receiving recess therein, the pressed together jaw members being adapted to receive and loosely hold an ampoule neck in the recess, a cutter plunger reciprocably extending through one of said jaw members in alignment with the recess, a substantially diamond hard cutter point mounted on the end of said cutter plunger and means yieldably resisting the movement of said plunger cutter point into said recess, said first and second mentioned yieldable means being so constructed and arranged that by pressing on said plunger, said jaw members are first squeezed together and thereafter upon continued pressing the cutter point is moved to contact the ampoule neck within the recess.

5. An ampoule neck cutter comprising a pair of lever arms, means intermediate their ends but somewhat adjacent one of their ends pivoting said arms together, means yieldably urging the other ends of said arms apart at least one of the adjacent faces of said one end of said arms being curved somewhat away from the other to permit limited movement of said other ends of said arms away from each other, said other ends of said lever arms each having a V recess extending laterally thereacross providing ampoule neck receiving upper and lower jaws, one of said jaws providing an anvil, a cutter point carrying plunger reciprocably extending through the apex of the V recess of the other of said jaws, means limiting the movement of said cutter point into and out of said jaw V recess, and yieldable means resisting the movement of said cutter point into said V recess, said first and second mentioned yieldable means being so constructed and arranged that by pressing on said cutter point carrying plunger, when an ampoule neck is placed in the V recess of the jaws, the jaws are first squeezed together to ampoule neck holding position and thereafter upon continued pressing the cutter point is moved to contact the ampoule neck within the V recess to cut the ampoule neck as the ampoule is rotated.
